(57) **CLAIM**

The ornamental design for a facial imaging booth, as shown and described.

DESCRIPTION

FIG. 1 is a front view of a facial imaging booth showing the new design;

FIG. 2 is a right side view thereof;

FIG. 3 is a left side view thereof;

FIG. 4 is a top view thereof;

FIG. 5 is a rear view thereof;

FIG. 6 is an isometric view as seen from the top, front and right side thereof;

FIG. 7 is an additional front view thereof, in a rotated configuration;

FIG. 8 is an additional isometric view as seen from the top, front and right side thereof, in the rotated configuration; and, FIG. 9 is a bottom view thereof.

The broken lines illustrate portions of the facial imaging booth that form no part of the claimed design.
